UNITED STATES PATENT OFFICE.

NEIL JOSEPH CAMPBELL, OF ALBANY, NEW YORK.

SAW-SET.

SPECIFICATION forming part of Letters Patent No. 629,151, dated July 18, 1899.

Application filed February 25, 1899. Serial No. 706,780. (No model.)

To all whom it may concern:

Be it known that I, NEIL JOSEPH CAMPBELL, a citizen of the United States, residing at Albany, in the county of Albany and State of New York, have invented certain new and useful Improvements in Saw-Sets, of which the following is a full and complete specification, such as will enable those skilled in the art to which it appertains to make and use the same.

This invention relates to saw-sets, and has more particular reference to a portable device of this class of compact form and rigidity and automatic action.

Reference is made to the accompanying drawings, forming part of this specification, in which like figures refer to like parts in the several views, and in which—

Figure 1 is a side elevation of a saw-set embodying my improved construction; Fig. 2, a plan view thereof; Fig. 3, a rear end elevation thereof; Fig. 4, a partial section through Fig. 2 upon the line 4 4, and Fig. 5 is a face view of the set-punch employed.

Referring more particularly to the drawings, 6 is a base or bed plate provided with a front member 6^a and a rear member 6^b and is composed, preferably, of iron, steel, or any rigid metal, forming a firm base for the set-arm and operative construction about to be described. The base 6 is provided with a plurality of countersunk screw-holes 7, by which it may be attached to a bench or other support. The rear portion 6^b of the base 6 is provided with an elevated portion or standard 8, which is composed of two members 8^a and 8^b, as shown in Figs. 2 and 3, and between said standard members is pivoted the rear end of an arched set-arm 9, a pivot-pin 10 passing through said standard members and said set-arm. A band-spring 11, the lower end of which is coiled about a pin 12, passing through the lower portions of the standard members 8^a and 8^b, describes a broad rearward curve and engages at its upper end a shoulder 9^a, formed upon the rear end portion of the set-arm 9, as shown in Figs. 1, 2, and 3, and the function of the spring 9 is to exert a depressing force upon the forward or operative end of the set-arm 9. Likewise pivoted between the standard members 8^a and 8^b is a trigger-

arm 12, mounted laterally of the set-arm 9 and upon the pivot-pin 10, the pivot-pin opening 13 thereof being elongated, as shown in dotted lines in Fig. 1, and the object of the elongation of the hole 13 is to allow of radial play of the arm 12. The set-arm 9 is transversely grooved in the upper rear portion thereof, forming a shoulder 14 forward of the shoulder 9^a. The trigger-arm 12 is provided at the side adjacent the set-arm 9 with a projecting pin 12^a, (best seen in Fig. 2,) and the pin 12^a is adapted to operate in connection with the shoulder 14, and by means thereof when the trigger-arm 12 is swung rearwardly the set-arm 9 will be raised against the elasticity of the spring 11. The trigger-arm 12 is also provided upon its inner end portion with an enlargement or lug 15, (best seen in Fig. 3,) and a trip-screw 16 passes therethrough, said screw 16 and lug being similarly threaded, and is adapted to operate in connection with a shoulder 17, formed upon the adjacent member of the standard 8, as shown at 8^b in the drawings. It is evident that when the trigger-arm 12 is rearwardly depressed, raising the set-arm 9, as described, at a given point in its path of movement, the trip-screw 16 will engage the shoulder 17, the trigger-arm 12 will be radially projected, and the spring 11 will depress 80 the forward or operative end of the set-arm 9.

The forward member 6^a of the base 6 is provided with a forwardly and downwardly projecting integral portion 6^c, and at the point of junction of said projection and the horizontal base member 6^a a solid anvil or disk 18 is set thereinto, and the disk 18 is beveled in its upper surface to coincide rearwardly with the upper surface of the base member 6^a and forwardly with the upper surface of the projection 6^c. The anvil 18 is preferably composed of hardened machine-steel. A set-punch 19 is set into the lower portion of the forward end of the set-arm 9 and detachably secured therein by a set-screw 20. A face view of the punch 19 is shown in Fig. 5, the lower or operative surface thereof being raised centrally and V-shaped in horizontal cross-section. The punch 19 is adapted to operate in connection with the anvil 18.

A cross-arm 21 is secured transversely of the base 6 by means of a set-screw 22, as

shown in Fig. 4, and the cross-arm is provided with a transverse elongated slot through which said screw 22 passes, and by means of which slot and screw it may be adjusted longitudinally of the base 6. The cross-arm 21 is recessed centrally of the forward edge thereof adjacent the anvil 18, as shown at 23 in dotted lines in Fig. 2. Laterally of the base 6 the cross-arm 21 is formed at an angle to the horizontal equivalent to the pitch of the base projection 6° and is provided in each of its outer end portions with a pair of stud-screws 24 24, about each of which is mounted a revoluble drum or collar 25, (shown in dotted lines in Fig. 2,) and above each collar and surrounding each screw 24 is mounted a washer 26, held in position by the head of the screw 24. About each pair of collars 25 25 is passed a continuous rubber band 27, and by means of the collars 25 the bands 27 are revoluble about the screws 24. Saw-guides 28 are secured one to either end portion of the cross-arm 21, and each comprises a flat base portion and a forward portion projecting upwardly at right angles therewith, and the flat base portion is slotted longitudinally to receive the lower end of a screw 24, and the saw-guide 25 may be adjusted upon said screw by means of said slot, which is elongated and 30 is shown in dotted lines at 29, Fig. 1, and secured in any adjusted position by means of a nut 30.

The saw-blade is designed to be placed upon the base projection 6°, the toothed portion 35 resting upon the guides 28, the teeth resting against the rubber bands 27, the tooth to be set resting upon the anvil 18 and projecting into the recess 23 of the cross-arm 21. An adjusting-screw 31 passes through an opening 40 in the outer end of the base projection 6°, which is similarly threaded, and by means thereof the pitch or angular position of the saw-blade with relation to the horizontal surface of the anvil 18 may be regulated and the set of the saw determined.

45 The operation of my device will be evident from the foregoing description, when taken in connection with the accompanying drawings and the following statement thereof.

50 The blade of the saw to be set is placed upon the projection 6° of the base 6 and the guides 28, the teeth thereof resting against the bands 27, and one tooth at a time may be brought into position over the anvil 18. 55 With a saw-tooth so placed the trigger-arm 12 is rearwardly depressed, the pin 12^a engaging the shoulder 14, and the set-arm 9 is raised against the elasticity of the spring 11. When the arms 9 and 12 have been pivotally 60 swung to such a point as shall bring the trip-screw 9^a into engagement with the shoulder 17, the trigger-arm 12 will begin to move radially as well as pivotally, due to the formation of the pivot-hole 13 of the arm 12, and 65 when this radial motion has continued to such an extent as to withdraw the pin 12^a from engagement with the shoulder 14, the set-arm

will be released, and the spring 11 will depress the set-arm 9, bringing the punch 19 into engagement with said saw-tooth, and setting the same upon the anvil 18. This operation is continued, moving the saw laterally of the saw-set device to the extent of one tooth for each blow of the set-arm 9, or as many blows as required to set each saw-tooth. 70 The revoluble rubber bands 27 will protect the teeth edges, and the guides 28 keep the saw-blade in proper position. The trip-screw 16 may be adjusted to produce blows of varying force by the set-arm 9. 75

It is evident that many changes may be made in the construction and arrangement of the parts of my device, and I claim all such as come within the scope of my invention.

Having fully described my invention, I 85 claim as new and desire to secure by Letters Patent—

1. In a device of the class described, a base portion provided with an anvil in the front 90 portion thereof, a spring-actuated set-arm provided with a punch and pivotally mounted in connection with the rear portion thereof, a trigger-arm pivotally mounted in connection with said base portion adjacent said set-arm, and provided with an elongated 95 pivot-opening by means of which it is radially movable, and having a projection, a shoulder being formed upon said set-arm, which said projection is adapted to engage to elevate said set-arm, and an adjustable screw 100 secured to said trigger-arm and which is adapted to engage said base portion in the downward movement of said trigger-arm to cause radial movement thereof and to withdraw said projection from engagement with said 105 shoulder, substantially as shown and described.

2. In a device of the class described, a base, a spring-actuated set-arm connected pivotally with said base and provided with a punch, 110 a trigger-arm pivotally mounted adjacent to said set-arm, and provided with means for engaging said set-arm, a trip-screw connected with said trigger-arm and adapted to engage said base to withdraw said means from said 115 set-arm, substantially as shown and described.

3. In a device of the class described, a base provided with an inclined projection, an anvil mounted in said base and in said projection 120 at the junction thereof, an adjusting-screw passing operatively through said base projection and adapted to regulate the set of a saw and a cross-arm mounted transversely of said base and provided at each end portion with a 125 pair of revolubly-mounted drums, and a flexible band passed revolubly about each pair of drums, and with a saw-guide secured to each end portion of said cross-arm and comprising an angular plate adjustably secured thereto, 130 substantially as shown and described.

4. In a device of the class described, a base, a cross-arm adjustably mounted thereon and provided at each end portion with a pair of

stud-screws, a collar revolvably mounted upon each of said screws, a flexible band passed revolvably about said collars, and a saw-guide comprising two angular plates adjustably secured to the under side of said cross-arm by means of the lower end of said stud-screws which pass through an elongated opening in each, and a nut fitting each of said screws and adapted to lock said saw-guide in adjusted position, substantially as shown and described.

5 5. In a device of the class described, a base, a cross-arm adjustably mounted thereon and provided at each end portion with a saw-guide comprising an angular plate, adjustably secured to the said cross-arm and adapted to engage the under face of a saw to be set, substantially as shown and described.

15 6. In a device of the class described, a base, a cross-arm mounted thereon and provided at each end portion with a pair of revolvably-mounted collars, and a flexible band passed

revolvably about said collars, substantially as shown and described.

7. In a device of the class described, a spring-actuated set-arm, a pivoted trigger-arm adapted to operate in connection therewith, and provided with an elongated pivot-opening whereby it is radially movable, and devices for limiting the downward movement of said trigger-arm to cause radial movement thereof, and to disconnect said trigger-arm from operative engagement with said set-arm, substantially as shown and described.

25 In testimony that I claim the foregoing as my invention I have signed my name, in presence of the subscribing witnesses, this 18th day 30 of February, 1899.

35 NEIL JOSEPH CAMPBELL.
